METHOD OF MAKING INNER SPRING
MATTRESSES

Robert F. Copeland, Cullman, Ala.

Application February 16, 1939, Serial No. 256,807

1 Claim. (Cl. 226—43)

This invention relates to an inner spring mattress and method of making the same, and it is a particular object of the invention to provide a mattress of this kind using fluffy or flake cotton such as comes from a gin or renovator instead of employing cotton in the form of a felt or batting such as now in use.

The novel features of my invention will hereinafter be definitely claimed.

In order that my invention may be the better understood, I will now proceed to describe the same with reference to the accompanying drawing, wherein:

Figure 1 is a view in perspective illustrating certain of the initial steps in my method of making an inner spring mattress;

Figure 2 is a view in perspective illustrating a further step;

Figure 3 is an enlarged sectional view taken longitudinally through Figure 2;

Figure 4 is a view similar to Figure 3 and of a diagrammatic character illustrating the further step of blowing the cotton fibre within the boxing, a second position of the nozzle being indicated by broken lines;

Figure 5 is a view similar to Figure 4 illustrating the second step of blowing cotton fibre with the boxing;

Figure 6 is a view in perspective illustrating diagrammatically the step of beating.

In making an inner spring mattress embodying my invention a boxing B is made of conventional dimensions, said boxing of course being of suitable textile fabric such as ticking. In seaming or connecting the side strips 1 to the top and bottom sheets 2 initially one end strip 1 is secured along only one marginal portion so that said end of the boxing B will be open to allow for the insertion therein of the inner spring S. This inner spring S is of any preferred fabrication but in all three directions is less than the corresponding interior dimensions of the boxing so that the desired space is allowed within the boxing B and around the spring S to receive the filler F.

Before being applied within the boxing B the spring S is suitably cased within a covering or bag C of burlap or kindred fabric. After the spring S with its covering C has been inserted within the boxing B the partially free end wall is then seamed into place except for a portion substantially at the transverse center of the boxing whereby is provided a relatively long filling opening 3.

The boxing B with the applied spring S is placed upon a suitable supporting surface with the filling opening 3 downwardly disposed and the applied spring S resting upon the lower sheet 2 of the boxing or that sheet or face wall in contact with the supporting surface. After the applied spring S has been properly centered within the boxing an elongated filling nozzle 4 is inserted

within the boxing through the filling opening 3 and caused to extend a slight distance between the top of the applied spring and the top sheet or wall 2. This nozzle 4 is of considerable length and in this operation it serves as a lever to partially depress the co-acting end portion of the applied spring S. The nozzle 4 is carried by the outer end portion of a hose 5 or the like leading from a suitable source of cotton fibre under pressure. The cotton fibre is of a fluffy or flake type such as when it leaves a gin or renovator. This cotton fibre is forced into the boxing B, as by a conventional blower, until a proper thickness of the cotton fibre has been applied within the boxing above the spring S and partially between the sides of the applied spring S and the side members 1 of the boxing. After this operation, the boxing B with applied spring S is reversed bringing the filling opening 3 uppermost. The nozzle 4 is then inserted into the boxing through this opening 3 and the loose or fluffy cotton fibre forced into the boxing into the space between the spring S and the now upper sheet or wall 2 of the boxing B and the now upper space between the side walls or strips 1 of the boxing and the sides of the spring S.

After the filling has been completed the nozzle 4 is withdrawn and the opening 3 closed. The opposite flat faces of the now filled boxing B are beaten with a long pole of a length substantially equal to the length of the complete mattress and the contact of the pole 5 with a wall 2 of the boxing B being lengthwise thereof. This beating is continued until after the applied filler F of cotton is of uniform thickness. The mattress is then placed on a finishing table to have the edge portions thereof suitably finished and also to have the conventional tufts applied.

I claim:

40 A method of making a mattress with an inner spring, comprising the steps of forming a box of woven material with one side wall open, inserting a compressible spring within the box through said open side with all three dimensions of the spring 45 materially less than the three corresponding dimensions of the box, then closing said wall of the box except for an opening at a marginal portion of the wall and at substantially the transverse center of the box, blowing fluffy cotton fiber between one side of the applied spring and the box through an elongated nozzle extending within the box through the opening, then inverting the box and blowing fluffy cotton into the box between the opposite side of the applied spring 50 and the box, using the nozzle after its second insertion within the box to compress the spring within the box to facilitate the blowing of the fiber within the box, and then removing the nozzle and closing the filling opening.
